UNITED STATES PATENT OFFICE.

JOHN KELLY, OF CHICAGO, ILLINOIS, ASSIGNOR OF TWO-THIRDS TO
THOMAS KELLY AND JAMES KELLY, OF SAME PLACE.

WATER-CLOSET.

SPECIFICATION forming part of Letters Patent No. 270,080, dated January 2, 1883.

Application filed June 28, 1882. (No model.)

To all whom it may concern:

Be it known that I, JOHN KELLY, of Chicago, in the county of Cook and State of Illinois, have invented certain new and useful Improvements in Water-Closets; and I do hereby declare that the following is a full, clear, and exact description thereof, reference being had to the accompanying drawings, and to the letters of reference marked thereon, which form a part of this specification.

This invention relates to improvements in water-closets; and it consists of the novel devices and combinations of devices hereinafter described and specifically claimed.

In the accompanying drawings, Figure 1 represents a longitudinal vertical section of a valve which I prefer to use in connection with my improvements as herein claimed, but to which I do not now make any claim, as it is designed 20 to make this the subject of a separate application, and Fig. 2 a cross-section through the center of the same. Fig. 3 is a sectional elevation of a water-closet, showing the valve as connected with the bowl and service-tank and the device of operating it by the depression of the seat, and Fig. 4 a sectional end view of the valve and of the pivotal operating-lever.

Corresponding letters in the several figures of the drawings designate like parts.

A denotes the globular casing of the valve, having base *a* for securing it by wood-screws and screw-nozzles *b*, *c*, and *d*, which form the water-passages, and an internally-screw-threaded neck, *e*. Through neck *e* is inserted into the globular casing a spindle, *B*, having two curved cranks, *f*, *f'*, that are diametrically opposite and form pivotal connections with the two valve-rods. A gudgeon at the end of the spindle *B* is inserted into a socketed boss, *i*, in the casing. A thimble, *C*, is passed over the spindle *B*, and is screwed into the neck *e* of the casing *A*, the inward end of which thimble is countersunk to form a bearing for a collar, *h*, of spindle *B*.

Upon the outward end of thimble *C* is screwed a cap-nut, *D*, that is to contain packing for forming a water-tight joint around spindle *B*. The exteriorly-projecting end of spindle *B* is squared for attaching a crank, *E*, and its ex-

tremity is screw-threaded for securing such 50 crank by a nut.

To the nozzle *b* is connected by a coupling-nut, *j*, the pipe *F*, that connects with the hydrant or city water-supply or with an elevated tank or reservoir. In the exterior end of this 55 nozzle *b* is formed the seat for a rubber valve, *G*, which, by a rod, *H*, is pivotally connected with crank *f* of spindle *B*.

To nozzle *c* of casing *A* is coupled a thimble, *I*, that forms the seat for a rubber valve, *K*, 60 which, by a rod, *L*, is pivotally connected to crank *f'* of spindle *B*. The valve *G* opens by being moved in an outward direction and the valve *K* by being moved in an inward direction in a manner that a partial rotation of spindle *B* while opening one of the valves will close the other simultaneously. These valves *G* and *K* are each cylindrical, with a conical end that fits the seat, and each is passed over the screw-threaded end of rod *H* or *L*, and is adjustably 70 secured thereto by a nut, *k*.

To the end of thimble *C* is connected a pipe, *J*, by a coupling-nut, *l*, the opposite end of which pipe *J* connects with the bowl *M* of the water-closet. To nozzle *d* of casing *A* is connected a pipe, *N*, by a coupling-nut, *m*, which pipe *N* connects with and leads into the service-tank *O*, that may be made square or cylindrical, and is closed on all sides. Into the top 75 of this tank is tapped a small pipe, *P*, which leads into the space between bowl *M* and seat-support *Q*. This pipe is provided with a stop-valve, *o*, and underneath the tapped opening for pipe *P*, inside the tank *O*, is placed a floating rubber ball, *p*, which is guided between 80 pending rods *p'*, and which will rise with the water, and will hermetically close the inlet to pipe *P*, thus admitting only a certain amount 85 of water into such tank *O*.

The crank *E* of valve-spindle *B* has suspended to its end a weight, *q*, and by a loop, *r*, it is coupled to one end of a lever, *W*, that at about its middle is pivotally attached to a standard, *s*. The opposite end of this lever *W* carries a knob-plate, *t*, upon which rests a stud, *u*, of the 90 hinged seat *S*, which is overbalanced or held on an incline by the weight *q*, so as to yield to a pressure or weight to be brought to bear 95

upon support Q, and to be raised again by the weight q as soon as such seat is released of any pressure.

The bowl M may be made of porcelain or metal, is to be steep conical, so as to prevent the adhesion of soil, and is to connect by a trap with the sewer. The pipe P is not made continuous, but is interposed by a box, T, which holds bottles v, filled with a disinfecting material to purify the air passing through such pipe P.

The operation of the valve and the entire apparatus is as follows, to wit: When a person occupies the seat S such seat will be depressed, and will swing the lever W, which will raise crank E, whereby valve G will be opened and valve K will be closed, thus forming a communication between the water-supply pipe F and the pipe that leads to service-tank O, which will now fill with water until the rubber ball p shuts off the air-escape. The air thus being forced out of tank O through pipe P passes through box T and comes in contact with the disinfecting material stored therein, and thence it escapes into the space above bowl M. As soon as the occupant rises and releases the seat S the weight will change the position of the valves by closing the water-supplying valve G and by opening valve K, when at once the water contained in tank O will rush through pipes N and J into and through the bowl M, washing away and carrying with it the soil. The space formerly occupied in tank O by the water will be replaced by air that is drawn through pipe P, and has on its way to pass through box T, where it is disinfected.

Instead of arranging the water-closet with a swinging seat, S, for operating the valves, a swinging foot-step in front of the seat may be provided that is connected with lever W.

As will be noticed, this device is very simple and has no parts that can wear out or get

out of order. A certain quantity of water will be automatically delivered for an after-wash with surety and without depending upon the attendance of the occupant. Another feature of the device is that the service-tank O will be filled only while the closet is occupied, and will be emptied after every release, so that no water remains therein to freeze. The valve herein described is adapted as well for a stop-cock in the same manner as the one described in Letters Patent No. 256,222, which were granted to me on April 11, 1882. In places where a heavy water-pressure is had the valve o may be closed, so as to prevent the escape of air from service-tank O. In such places the pipe P and float-valve p may be entirely dispensed with, and the disinfecting-chamber T may be made to communicate with pipe N for disinfecting the water that is passed through the bowl.

What I claim is—

1. In a water-closet, a valve substantially as described, and connected by pipe N with the service-tank O, such tank having stop-valve o, float-valve p, and air-escape pipe P, the whole to operate substantially in the manner herein set forth.

2. In a water-closet, a valve substantially as described, and connected by pipe N with the service-tank O, such tank having float-valve p, and air-escape pipe P, that is interposed by a chamber, T, containing disinfecting material, all substantially as and for the purpose described and shown.

In testimony that I claim the foregoing as my invention I affix my signature in presence of two witnesses.

JOHN KELLY.
